UNITED STATES PATENT OFFICE.

ADAM G. BERKEBILE, OF SOMERSET, PENNSYLVANIA.

TRACK GAUGE.

Application filed July 6, 1926. Serial No. 120,729.

This invention aims to provide a novel form of gauge for use in laying track, the structure being of peculiar utility in the hands of coal miners, and others, who desire an extremely portable and light article.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:—

Figure 1 shows in elevation, a device constructed in accordance with the invention, parts being broken away;

Figure 2 is a section taken about on the line 2—2 of Figure 1; and

Figure 3 is an elevation showing one of the brackets.

In carrying out the invention, there is provided a pair of metal brackets. Each bracket is like the other, and one bracket, therefore, will be described.

The bracket includes a main member 1 merging into a loop-shaped body 2 terminating in an arm 3 disposed about parallel to the main member 1, the end of the arm 3 being thinned as at 4 and being provided with teeth which are shown at 5. At its upper end, the main member 1 is provided with an extension 6 located approximately at right angles to the main member 1 and at right angles to the arm 3.

In the extension 6 is threaded a clamp screw 7 which is located in line with the arm 3.

Two brackets, constructed as described,

are slipped on a bar 8, or the like, the teeth 5 on the arm 3 biting into the lower edge of the bar 8, and the clamp screw 7 being advanced into the upper end of the bar, the main member 1 engaging one edge of the bar, all as shown in Figure 2. The result is that the bracket is held securely on the bar and the depending body portions 2 may be placed against the treads of a pair of rails 9, as and for a purpose well understood by any one who has had any experience in laying track.

A miner or other person can carry the brackets in his pocket without inconvenience, select any kind of a piece of wood or other material which may happen to be at hand, employ it as the bar 8, fasten the brackets thereon, and proceed with his track laying.

What is claimed is:—

In a railway track gauge, brackets each comprising a main member provided at one end with a loop-shaped body terminating in an arm disposed approximately parallel to the main member, the main member being supplied at its opposite end with an extension disposed at an angle to the arm, a clamping device in the extension, and a bar bound between the arm and the clamping device of each bracket and abutting against the main member of each bracket, the loop-shaped body projecting prominently with respect to the bar, all portions of the outer edge of each loop-shaped body being in the same plane, and the aforesaid abutment between the bar and the main members serving to aid in holding each loop-shaped body in such a position that the said plane will be disposed at right angles to the length of the bar.

In testimony that I claim the foregoing as my own, I have hereto affixed my signature.

ADAM G. BERKEBILE.
